TOY STATIONARY ENGINE

Harold L. Snavely, Oak Lawn, Ill.

Application July 30, 1948, Serial No. 147,845

Term of patent 3½ years

(Cl. D34—15)

To all whom it may concern:

Be it known that I, Harold L. Snavely, a citizen of the United States, residing in Oak Lawn, county of Cook, and State of Illinois, have invented a new, original, and ornamental Design for a Toy Stationary Engine, of which the following is a specification, reference being had to the accompanying drawing, forming a part there-of.

Fig. 1 is a perspective view of the toy stationary engine, showing my new design.

Fig. 2 is a plan view to a reduced scale of the toy stationary engine.

Fig. 3 is a side elevational view to a reduced scale, and

Fig. 4 is an end elevational view to a reduced scale.

I claim:

The ornamental design for a toy stationary engine, as shown.

HAROLD L. SNAVELY.
